UNITED STATES PATENT OFFICE.

CHARLES S. BOSSIE, OF NEW YORK, N. Y.

COLLAPSIBLE WASHING MACHINE.

Application filed March 24, 1928. Serial No. 264,328.

This invention relates to new and useful improvements in clothes washing machines, and has for its principal object to provide simple means for permitting the washing machine to be hidden from view when not in use.

Another object of this invention is to provide a washing machine which in ordinary use is supported on the sides of the ordinary washtub.

A further object of this invention is to provide a washing machine which is supported on the sides of the washtub and additional supports resting on the faucets 15 inside of the washtub and base of washtub.

A further object of this invention is to provide a swingable washer that rotates in and out of a washtub and adjustable means of supporting the washer in both positions.

20 A further object of this invention is to provide a swingable washer on adjustable pivots.

A further object of this invention is to provide a swingable washer rotating on 25 adjustable pivots which are supported on faucets of a washtub and the base of the washtub.

With these and other objects in view, the invention consists in the novel combination 30 and arrangement of parts which will be fully set forth in the following specification and accompanying drawings, in which,

Fig. 1, is a vertical view of the device.

Fig. 2, is a plan view of the device.

35 Fig. 3, is a partial view of the washer when hidden from view.

Fig. 4, shows a detail of the hook.

Fig. 5, shows a detail of the socket.

In the drawings the numeral 1, represents 40 a motor which through a coupling 2, drives a worm gear 3. This worm gear in turn drives a toothed gear 4 which is fastened to an axle 5. A casing 6 encloses the gearing and has lugs 4^a and 4^b for placing thereon a clothes wringer not shown and driven by driver 7.

To the axle 5 there is fastened a short revolving lever 8, at the end of which is a short shaft 9. On this shaft 9, a connection to an oscillating lever 11 is through 50 shaft 12.

The oscillating lever 11 is affixed to a rocker arm shaft 13. The other end of the rocker arm shaft 13 is formed into a receiving socket 14 and notched portion 14^a.

On the notched portion 14^a there is sus-

pended a rocker arm 15 the center of which spans and is frictionally engageable with the notched portion 14^a. A latch 15^a is provided at the bottom of the portions forming the span. This latch can be locked or unlocked to prevent the rocker arm 15 from being displaced from the notched portion 14^a. The latch 15^a is removable at will.

A handle 15^b is provided for easy manipulation of the rocker arm when removing same from the machine.

On the ends of the arm 15 there are suspended oscillative links 16 and 17. At the bottom of the links there are two pan 70 shaped devices 18 and 19 which perform the operation of kneading the clothes when washing.

The links 16 and 17 are connected by a horizontal bar 20. This bar prevents the 75 links from leaving their required positions.

The bar 20 is connected to an elliptical hook 50 through a pin 51 around which the bar 20 is adapted to oscillate.

The upper part of the hook 50 has a 80 square groove 52 which is adapted to snugly fit over a lug 53 projecting from the motor casing or from any other permanent part of the device.

In operation the kneading is performed 85 by the oscillation of the rocker arm 15. The links 16 and 17 are held in place by the bar 20 and since the hook 50 is held fast on the lug 53 the bar oscillates on the pin 51 as a fulcrum. In this manner the kneading is 90 performed in a substantial up and down motion.

A base 21 supports the motor, and all other mechanism operated thereby, and in addition has two downwardly projecting 95 extensions 22 and 23. The extensions have perforations 24 for raising or lowering of the base 21.

Adjustable supports 25 and 26 co-operate with the extensions 22 and 23 through the 100 medium of a bar 27 and collars 28^a and 28^b and the other support held by collars 28^c and 28^d, each pair of collars holding the adjustable support to the extension.

The adjustable supports 25 and 26 consists 105 of telescopic parts 54 and 55, the former having a groove 56 wherein a tongue from part 55 travels up or down and is held in any desired position by means of bolt 57 and wing nut 58.

In order to prevent overturning of the supports 25 and 26, an additional support

is provided. This additional support is formed by forming two apertures in each support and inserting rods 59 and 60. One end of each rod has a loop as 62 and 63 with latches 64 and 65 spanning the ends of the loops. The loops have their ends threaded and wing nuts 66 and 67 hold the latches tightly in place.

The loops 62 and 63 are adapted to encircle faucets 68 and 69. The distance between the faucets may be regulated by forcing the loops towards or away from each other and tightening the set screws in the collars 59^a and 60^a around the rods at the 15 adjustable supports.

Underneath the base 21 two bosses 29 and 30 are affixed. To these bosses are attached swingable supports 31 and 32. The support 31 has its lower end 33 right angled, so as to fit over a smooth or otherwise plane 20 surface as a washtub 70.

The support 32 swings on boss 30 through pin 36. This support is made in two parts 37 and 38. The latter portion 38 has a slot 39 through which a bolt 40 travels and a wing nut 41 holds the two portions of the support at any desired length. The lower end of support 32 is also right angled as at 42 to fit the plane surface of the washtub 70.

30 In operation of the device the washing machine is set so that supports 31 and 32 are resting on the edges of the ordinary washtub 70. Wherever necessary the support 32 is either lengthened or shortened to 35 fit any size washtub. The loops 68 and 69 are then spaced apart and placed over the faucets in the washtub and the latches underneath closed and locked.

The adjustable supports 25 and 26 are 40 then fitted so that the bottom of each rests on the bottom of the washtub.

When washing is completed and the wash-

tub drained, the entire washing machine may then be disposed and hidden from view by first opening the latch 15^a and removing 45 the rocker arm 15 with the pans 18 and 19. Then lifting the machine and base 21 and removing the supports 31 and 32 from the sides of the washtub 70. These supports may be folded directly underneath the base 50 21.

The base and motor may then be swung about the rod 27 until the casing 71 about the motor touches the bottom of the wash-tub. The rocker arm and pans may then be 55 placed alongside of the motor.

What I claim is:

1. A washing machine comprising, in combination, a table for supporting washing apparatus, and a tub with faucets set a distance apart, supports leaning against a side of the tub and held in position by adjustable means fastened to said faucets, means for connecting said table and supports in pivotal relation, and additional means for holding 60 said table against the sides of said tub when desired.

2. A washing machine comprising, in combination, a table for supporting washing apparatus, and a tub with faucets set a distance apart, adjustable supports positioned against a side of the tub and held in position by adjustable rods fastened to said faucets, said supports extending to within a short distance of the edge of the top of the tub, means for connecting said table and supports in pivotal relation, and additional means for holding said table against the sides of said tub when desired.

Signed at New York, New York, in the 80 county of New York and State of New York this 15th day of March, A. D. 1928.

CHARLES S. BOSSIE.
